BULLDOZER

George S. Allin, Seattle, Wash.

Application July 26, 1937, Serial No. 155,729

1 Claim. (Cl. 37—144)

This invention relates to improvements in bulldozers, and it has reference more particularly to novel means, of a manually actuated kind, simple in design, relatively inexpensive in construction, effective, quick acting and easily operated, for lifting the bulldozer blade to any of its different working levels.

It is the principal object of this invention to provide a manual means of the above character, utilizing as a part thereof hydraulic cylinders and a hand pump whereby a hydraulic pressure may be built up in the cylinders to actuate pistons in the cylinders to elevate the blade to a desired height; the pump also being adapted to provide for relief of pressure medium from the cylinders whereby the blade, by reason of its own weight, will move to a lower position.

Other objects of the invention reside in the manner in which the hydraulic cylinders are mounted and connected so that the strain and stresses of lifting the blade will be applied to the track frames as differentiated from being applied to the tractor main frame.

Still further objects of the invention reside in the details of construction and combination of parts, and mode of operation, as will hereinafter be fully described.

In accomplishing these and other objects of the invention, I have provided the improved details of construction, the preferred forms of which are illustrated in the accompanying drawings, wherein—

Fig. 1 is a side view of a bulldozer embodying the present invention.

Fig. 2 is a partial plan view of the same.

Fig. 3 is a detail of a hydraulic cylinder, as connected to the track frame, and showing diagrammatically the hand pump as connected with the cylinders.

Fig. 4 is an enlarged vertical cross section of the pump, showing its valve connections.

Fig. 5 is a cross sectional view, on the line 5—5 in Fig. 4, showing the relief valve connections.

While the present invention may well be applied to tractors of various kinds, and also may be used with bulldozer blades and mounting of different designs, it has here been shown as applied to a tractor of the crawler track type and with a blade mounting frame that is pivoted to a dead axle. It is to be understood that this is for purpose of explanation only and not necessarily a limitation.

Referring more in detail to the drawings—

In its present embodiment, the bulldozer utilizes a tractor of the crawler, or self laying

track type. The tractor is designated in its entirety by reference numeral 1, and it includes the usual main frame structure, or chassis 2, wherein is mounted an engine, designated at 3. At opposite sides of the main frame, or chassis 2, are the track mounting frames designated generally by reference character 4, and at the opposite ends of these frames the track mounting and driving wheels 5 and 6 are contained therein. The endless traction belts, or tracks, 7 are extended about the wheels 5 and 6. Between these wheels, the upper runs of the endless track belts are supported by idler rollers 8 and the lower run is likewise guided and held in ground contact by idlers 9; the idlers 8 and 9 being supported from the track frames 4 as is the usual practice. The means for driving the tracks is not herein shown as it constitutes no part of the present invention, but may be through any suitable kind of connections with the engine 3.

The two track frames 4 are arranged symmetrically at opposite sides of the main frame of the tractor and near their rearward ends are pivoted for oscillating action upon the opposite ends of a dead axle 15 which extends transversely through and is fixed in the main frame of the tractor as a support for the latter. The forward end of the tractor would best be supported from the track frames 4 through the mediacy of springs, or other suitable means, not shown, to permit a relative upward and downward movement of the tracks incident to travel over uneven surfaces.

The bulldozer structure comprises also the usual transverse blade 18, located forwardly of the tractor and supported through the mediacy of a frame comprising two thrust beams 20—20 extending along the opposite sides of the tractor and operatively connected at their forward ends to the blade structure. At their rearward ends, these beams have brackets 23 fixed thereto and these, in turn, are formed with bearings whereby the brackets are rotatably fitted to the opposite end portions of the dead axle 15 at the outside of the tracks. Nuts 24 on the ends of the dead axle 15 hold the parts properly assembled.

The means for supporting the forward ends of the beams 20—20, to hold the blade in working position, or to lift it clear of the ground, comprises, at each side of the tractor, a hydraulic cylinder 30. These cylinders have fixed mountings in trusses rigidly mounted on the beams adjacent their rearward ends. Each of these trusses comprises an upright, rear leg member 31, that has its lower end solidly fixed to its beam 20, 55

with its upper portion, which leans slightly rearwardly, solidly fixed to a channel beam 33, which extends forwardly and downwardly and is fixed solidly to the beam 20 at some distance forwardly of the upright leg; thus the beams 20, 31 and 33 at each side, form a triangular truss in a vertical plane parallel with the tractor and upon the beam 20.

The hydraulic cylinders 30 are of rather small diameter but are relatively long and are contained in or disposed alongside of the beams 33 and have their upper ends fixed by bolts 35 to their respective trusses at the junction of legs 31 and beams 33.

16 Each cylinder 30 is fitted with a piston 40 and this has a piston rod 41 extending from the lower end of the cylinder. To the rods are attached cables 42 which extend beneath sheave wheels 44 rotatably mounted in the lower end portions 20 of the beams 33, or on the beams 20, then extend directly upward and at their upper ends are connected to brackets 48 that are fixed solidly upon the track frames, across the top runs of the track belts.

25 It is quite apparent that with this arrangement of cylinders and cable connections, the retraction of the pistons and cables will cause the beams 20-20 to be lifted, thereby to lift the blade accordingly.

30 The manual means which I have provided for controlling the movement of the pistons in the hydraulic cylinders comprises a hydraulic hand pump 50 operated by a vertical handle or lever 51. As shown diagrammatically in Fig. 4, the pump 35 comprises two pump cylinders 54 and 55, each with a pump piston 57. The pistons are connected by links 58 with the lever 51. Also, the two cylinders have pipe connections 59 and 60 with a supply reservoir 61; each pipe having a 40 back check valve 62. Also, each pump cylinder has an outlet pipe 64 with back check valve 65. The

6 pipes 64 are connected with a cross pipe 68 which, at its opposite ends, respectively, connects with the lower ends of the hydraulic cylinders 30-30. There is also a return pipe 70 leading back to the reservoir from the pipe 64 and containing a 6 normally closed valve 75 that is adapted to be opened by a sidewise movement of the handle 51 bringing a lug 51x thereon into contact with the valve opening rod 76. When this rod is depressed, the valve 75 is opened, the hydraulic 10 medium in the two cylinders 30-30 will then flow back to the reservoir and allow lowering of the blade until the valve is again closed.

15 By this above described means, the blade may be manually lifted, easily and quickly, to any 15 desired height within its limits of travel.

Having thus described my invention, what I claim as new therein and desire to secure by Letters Patent is:

In a bulldozer, a tractor including track frames 20 at opposite sides of a main frame, a blade mounting frame pivotally supported at its rearward end from the tractor and extending forwardly thereof for vertical oscillation at its forward end, a blade mounted by said frame, a truss mounted on the 25 blade mounting frame near the pivoted end and comprising an upright member and a downwardly and forwardly inclined strut, a hydraulic cylinder mounted within the strut lengthwise thereof, a sheave wheel fixed on the blade mounting frame 30 at the lower end of the strut, a bracket fixed on the track frame and overhanging the said sheave wheel, a piston in the said cylinder, a cable attached to the bracket and extending beneath the sheave wheel and having fixed connection with 35 the piston, and means operable to apply hydraulic pressure medium to the cylinder for controlling the piston movement for adjusting the position of the blade mounting frame.
